CLAIM

The ornamental design for a latch housing with push button, as shown and described.

DESCRIPTION

FIG. 1 is a perspective view of a latch housing with push button embodying the design of the present invention;

FIG. 2 is an end elevational view thereof;

FIG. 3 is a bottom plan view thereof;

FIG. 4 is a side elevational view thereof;

FIG. 5 is a sectional view thereof as seen from a plane indicated by a line 5—5 in FIG. 2; and,

FIG. 6 is a top plan view thereof on an enlarged scale.
